(57) **CLAIM**

The ornamental design for a rectangular parallelepiped fluid storage and dispensing vessel, as shown and described.

DESCRIPTION

FIG. 1 is a perspective view of a rectangular parallelepiped fluid storage and dispensing vessel showing our new design; FIG. 2 is a front elevation view thereof, wherein such front elevation view is identical in appearance to each of the back elevation view, the left-hand side elevation view and the right-hand side elevation view of the vessel;

FIG. 3 is a top plan view thereof; and,

FIG. 4 is a bottom plan view thereof.

The broken lines showing are for illustrative purposes and form no part of the claimed design.
